United States Patent Office.

FREDERICK M. UNTIEDT, OF EAST ORANGE, ASSIGNOR TO HIMSELF AND WILLIAM MARTIN, OF NEWARK, NEW JERSEY.

Letters Patent No. 91,795, dated June 22, 1869.

IMPROVEMENT IN HAND-CHOPPING KNIVES.

The Schedule referred to in these Letters Patent and making part of the same.

To all whom it may concern:

Be it known that I, FREDERICK M. UNTIEDT, of East Orange, county of Essex, and State of New Jersey, have made certain Improvements in Hand-Chopping Knives; and I do hereby declare the following to be a full and exact description of the same, reference being had to the accompanying drawings, as forming part of this specification.

My improvement consists in the manner of forming a knife, with blades standing in angles relatively to each other.

Figure 1 is a perspective view of the knife complete.

Figure 2 shows one piece of steel in an edge view, bent in a form for being combined with another, or other pieces of bent steel to form a knife.

Figure 3 is the shank, with an end view of the same.

Sheet-steel of the requisite length, width, and breadth is formed in suitable dies to the angle shown in fig. 2, or to any other desired angle.

Two of the angular pieces are held together at the points of the angles, by the two shank-pieces, *a* and *b*,

fig. 3, one of which extending down the inner part of each angle. The two are held securely together by rivets, or screws, at the same time holding in position the blades of the knives.

The two shank-pieces, *a* and *b*, entering the handle *c*, are thereby prevented from separating when the strain of work comes upon the blades.

The handle is formed convenient for chopping, by being held in use by either the vertical or cross-piece thereof.

What I claim, and desire to secure by Letters Patent, is—

As a new article of manufacture, the chopping-knife, fig. 1, when its parts are formed and combined substantially in the manner and for the purpose shown and described.

FREDERICK M. UNTIEDT.
